UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING MACHINE.

1,404,705.

Specification of Letters Patent. Patented Jan. 24, 1922.

Application filed May 3, 1919. Serial No. 294,392.

To all whom it may concern:

Be it known that I, ALBERT H. DE VOE, a citizen of the United States, residing at Westfield, in the county of Union and State 5 of New Jersey, have invented certain new and useful Improvements in Sewing Machines, of which the following is a specification, reference being had therein to the accompanying drawings.

10 This invention relates to sewing machines and especially to the type thereof used for domestic or household purposes.

It aims to provide a construction and arrangement of head and parts therein which 15 will allow sleeves and circular work to be slipped up over the arm especially where such work is too small to be done by manipulation of the material or to be accomplished otherwise on a household machine. Further 20 it aims to improve the general arrangement of driving mechanism for the upper and lower stitch-forming instrumentalities. Also it aims to reduce the head in size as much 25 as possible and to this end it contemplates a new and improved mechanism for operating the needle-bar from within the confines of the head. And finally it aims to 30 control the needle-thread from within the overhanging arm so that the arm may be kept clear and free for the ready passage of work thereover.

The construction is applied to a flat bed machine of the family type having a main-shaft journaled transversely in its vertical 35 standard which supports an overhanging arm terminating in a depending head which is joined to the arm on smooth curved lines. The stitching mechanism comprises a loop-taking device below the cloth-plate and a 40 rectilinearly movable needle above the cloth-plate each of which is actuated from the before mentioned main-shaft in the vertical standard.

The needle-bar operating mechanism includes an endwise shiftable member which 45 is pivoted directly to the upper end of the needle-bar whose upper limit of travel falls short of the inside of the head of the machine, the head being free of projections 50 and unobstructed externally for the ready passage thereover of circular work such as sleeves. A take-up is located adjacent and operated from within the vertical standard where it is accessible for threading and at 55 such location that no thread lies on the ex-

ternal surface of the arm where it would be likely to be broken.

The invention is illustrated in the accompanying drawings in which Fig. 1 is a longitudinal vertical section through the overhanging arm and partly through the flat cloth-plate of the machine. Fig. 2 is a transverse vertical section through the vertical standard looking toward the belt-wheel on the main-shaft, and Fig. 3 is a bottom plan 60 view of the mechanism beneath the cloth-plate.

In the drawings the needle 1 secured to the lower end of a rectilinearly movable needle-bar 2 is operated through a pivotal 70 connection 3 at its upper end by an endwise shiftable rocking member or link 4 supported and actuated by parallel and similar links 5 and 6 pinned to an actuating rock-lever 7 on opposite sides respectively of its 75 supporting fulcrum pin 8. The rock-lever 7 and endwise shiftable member or link 4 are disposed, roughly speaking, in parallelism and are maintained in such relation while operating by the substantially parallel 80 links 5—6.

The rear end of the rock-lever 7 is pinned at 9 to one end of a driving link 10 having a pin 11 projecting laterally into a socket provided in a strap or collar 12 embracing a 85 crank 13 on the main-shaft 14, while the opposite end of the link 10 is joined to a bell-crank 15 pivoted on a pin 16 parallel with the fulcrum-pin 8 of the rock-lever, the bell-crank 15 being connected by a ball-and-90 socket joint 16' to a rod 17 having at its opposite end a ball-and-socket connection 18 with a loop-taker 19 and intermediate driving mechanism indicated generally by the numeral 20 and fully disclosed in patent to 95 Diehl & Grieb, No. 663,696, Dec. 11, 1900.

On the main-shaft 14, to the right of the crank 13 as viewed in Fig. 1, is a cam 21 which is embraced by the fork-ended-lever 22 pivoted to a block 23 which is slidable in 100 a channel member 24 which may be swung about the supporting screw 25 by the forwardly extending thumb-screw 26 whose inner end is grooved at 27 to embrace the stud 28 integral with the channel member 24. By shifting the stud 28 of the channel member the inclination of its channel may be varied and the feed-dog, whose supported end appears at 29, may be moved more or less as desired through the crank-arm 30 on 110

the rock-shaft 31 carrying the feed-rocker 32 and through the feed-dog supporting bar 33 which is adapted to be moved up and down intermittently by a cam (not shown) 5 on the loop-taker shaft as is fully disclosed in patent to Diehl & Grieb, No. 663,673, Dec. 11, 1900. Specifically the feeding mechanism forms no part of the present invention.

On the main-shaft 14, to the left of the 10 crank 13 as viewed in Fig. 1, is fixed a crank-arm 34 carrying a crank-pin 35 actuating an elbow-lever 36 which is hinged at the junction of its arms at 37 to a link 38 anchored at 39 to one side of the vertical standard. 15 The other end of the elbow-lever 36 is universally connected in any convenient manner to a link 40 pinned at 41 to the short arm of a take-up bellerank 42 fulcrumed on the screw 43 to a fixed part 44 of the vertical 20 standard and having its long arm extending vertically upward into the rear end of the overhanging arm where it is apertured at 45 to receive and control the needle-thread in a manner required by the stitch-forming mechanism.

While the invention has been described in its preferred form it is to be distinctly understood that the invention is not limited to the specific construction set forth, as the 30 same is only illustrative of the principles of operation which are capable of incorporation in metal in various forms, and that the invention comprehends all construction within the scope of the accompanying claims.

35 Having thus set forth the nature of the invention, what I claim herein is—

1. In a sewing machine, an overhanging arm having a head, a needle-bar mounted to reciprocate in said head, a lever fulcrumed 40 at a fixed point in its length, means for operating said lever, and a member with direct operative connection to said needle-bar and with intermediate connection to said lever permitting endwise movement of the 45 member relative to the lever while the former is oscillated by the latter.

2. In a sewing machine, an overhanging arm having a head, a rectilinearly movable needle-bar in said head, a rock-lever, means 50 for operating said rock-lever, and a lever member pivoted adjacent one end directly to said needle-bar whereby said end moves rectilinearly said lever member being actuated by said rock-lever through connections 55 permitting endwise movement of the member relative to the rock-lever.

3. In a sewing machine, an overhanging arm, a needle-bar mounted to reciprocate in said arm, a lever, means for operating said 60 lever, and a member at one end connected to said needle-bar and at spaced intervals to one side of said end connected by links to said lever.

4. In a sewing machine, an overhanging 65 arm, a needle-bar, a lever fulcrumed inter-

mediate its ends within the overhanging arm, means for operating said lever, and a member pivoted directly to said needle-bar and linked to the lever at opposite sides of the lever's fulcrum.

5. In a sewing machine, an overhanging arm, a needle-bar mounted to reciprocate therein, a lever fulcrumed intermediate its ends within the arm, means for operating said lever, and a member pivoted directly to said needle-bar and connected by substantially parallel links to said lever.

6. A needle-bar operating mechanism for sewing machines having a rectilinearly movable needle-bar, a lever, means for operating said lever, a member pivoted directly to said needle-bar, and spaced links connecting said lever and member.

7. In a sewing machine, a vertical standard, an overhanging arm supported by said vertical standard, said overhanging arm terminating in a bent depending head which is externally unobstructed for the free and ready passage of work thereover, a main-shaft sustained by the vertical standard, a lever sustained within the overhanging arm, means connecting said main-shaft and lever for oscillating the latter, a needle-bar mounted for rectilinear movement within the head and projecting therethrough only from the lower end of the head, a member connected directly to said needle-bar, said member and lever being disposed in substantial parallelism entirely within the confines of the overhanging arm, and means for actuating said member from said lever and maintaining the member and lever in parallelism.

8. In a sewing machine, an overhanging arm, a needle-bar mounted to reciprocate therein, a lever fulcrumed in said arm, means 105 for operating said lever, and a member connected to said needle-bar and at spaced intervals having link connection with said lever.

9. In a sewing machine, an overhanging arm, a needle-bar mounted to reciprocate therein, a lever fulcrumed at a fixed point in its length to said arm, means for operating said lever, and means for transmitting movement from said lever to said needle-bar comprising a member connected to said bar and having a connection with said lever which permits an endwise movement relative thereto.

10. In a sewing machine, an overhanging arm having a head, a needle, a needle-bar slidably supported in said head, needle-bar operating mechanism housed within said arm including a link pivoted directly to said needle-bar, a lever fulcrumed intermediate its 125 ends within said overhanging arm, links connecting the opposite ends of said lever with the first-mentioned link, and means for actuating the said lever.

11. In a flat-bed sewing machine, a verti-

cal standard, an overhanging arm supported by said standard, a depending head, a bent portion connecting said arm and said depending head, said arm and said depending head and bent portion being externally smooth, upper stitch-forming instrumentalities enclosed within said arm, a main-shaft journaled transversely in said vertical standard intermediate its ends, lower stitch-forming instrumentalities arranged below the flat-bed and operative connections between said main-shaft and each of said upper and lower stitch-forming instrumentalities. 5

10 12. In a sewing machine, a vertical standard, an overhanging arm supported by said standard, a depending head, a bent portion connecting said arm and said depending head, said arm and said depending head and bent portion being externally smooth, upper 15 stitch-forming instrumentalities completely enclosed within said arm, a main-shaft journaled transversely in said vertical standard intermediate its ends, lower stitch-forming instrumentalities, a crank-element on said 20 main-shaft, a member slidably connected to said crank-element, and operative connections between said members and each of said 25 upper and lower instrumentalities. 25

13. In a flat-bed sewing machine, a vertical standard, an overhanging arm supported by said standard, a depending head, a bent portion connecting said arm and said depending head, said arm and said depending 30

head and bent portions being externally smooth, upper stitch-forming instrumentalities completely enclosed within said arm, a main-shaft journaled transversely in said vertical standard intermediate its ends, lower 35 stitch-forming instrumentalities arranged below the flat-bed, a crank-element on said main-shaft, a member slidably connected intermediate its ends to said crank-element, levers operatively connected to the ends of said member, and operative connections between each of said levers and each of said 40 upper and lower instrumentalities. 45

14. In a flat-bed sewing machine, a vertical standard, an overhanging arm supported by said standard, a depending portion, a bent portion connecting said arm and said 50 depending portion, said arm and portions being externally free of obstructions to the passage of a tubular article thereover, a needle, needle-operating mechanism housed within said arm, a cooperating lock stitch forming instrumentality arranged below the flat-bed, a main-shaft journaled transversely in said standard, a take-up housed within said vertical standard, and means connecting said main-shaft with said take-up, said needle and said lower lock stitch forming instrumentality for operating the same to form 55 stitches. 60

In testimony whereof, I have signed my name to this specification.

ALBERT H. DE VOE.
